Specification for Design.

Patented May 3, 1921.

Application filed September 20, 1920. Serial No. 411,675. Term of patent 7 years.

To all whom it may concern:

Be it known that I, ALFRED G. KINTZ, a citizen of the United States, residing at Wallingford, county of New Haven and State of Connecticut, have invented a new, original, and ornamental Design for Backs for Hand - Mirrors, Brushes, &c., of which the following is a specification, reference being had to the accompanying drawing, forming a part thereof.

Figure 1 is a front view of a back embodying my new design;

Fig. 2 is a back view of the same; and, Fig. 3 is an end view.

These figures taken together show my complete design.

I claim:

The ornamental design for a back for hand mirrors, brushes or similar articles as shown.

ALFRED G. KINTZ.
